ATTORNEY.

UNITED STATES PATENT OFFICE

CHARLES F. DINGMAN, OF PALMER, MASSACHUSETTS

DISPLAY WINDOW CONSTRUCTION

Application filed September 30, 1929, Serial No. 396,233. Renewed March 24, 1932.

This invention relates to improvements in display window construction.

An object of the invention is to so construct such a window that the articles of merchandise which are on display for sale will be illuminated so as to enable an observer from the outside or on the street side of the window to obtain a view of the articles that is complete and correct.

At the present time, the light rays from an outside source of the window are reflected back from the outer surface, to such an extent that a person on the outside of a show window does not obtain a clear view of the merchandise which is being displayed. In other words, it is an object of the present invention to minimize as much as possible the reflecting of images of passers-by. This object, I attain by making the quantity of light transmitted through the show window glass, preferably from the merchandise displayed, approach equally the amount of light reflected off from the outer surface of the show window glass.

For this purpose, light is admitted to the interior of the window display space through a transom above the show window and reflected downward onto the merchandise, as will be fully described in the body of the description, when taken in connection with the accompanying sheet of drawing.

Referring to the drawing in detail:

1 designates the interior space of the show window in which the articles of merchandise to be displayed are placed, as for example, a shoe indicated at 2 on the rest or rack 3. 4 designates a transom window that is located above the main plate glass or outside show window 5. 6 designates a portion of a show window ceiling, 7 an opening or space between the end of the ceiling 6 and the rear wall 8 in which wall a window 9 may or may not be located. 10 is a member for reflecting the horizontal rays of light, indicated at 11, downward, as shown at 12. These rays enter, or pass through the transom 4, as shown, and are reflected from the surface 10 downward onto the article of merchandise 2 and from the surface of which article they are reflected directly outward,

indicated at 13, through the window 5 with the result that an observer on the outside of this window 5 will be enabled to obtain a clear and unobstructed view of the article shown, for example, at 2.

In other words, the article is fully "lighted up", so to speak.

If desired, a supplemental, or auxiliary mirror or light reflecting member may be employed, as shown at 14. This reflects the ray of light 15 from the surface 10 directly upwards toward the bottom of the bracket 3 and the show, or other article, indicated at 2, as illustrated by the arrows 16. By means of the rays 12, 15 and 16 the article is fully lighted up, so that an observer from the outside of the plate glass 5 will clearly see an article, since the inside rays 13, 16 and 17 will be stronger than the external rays from the outer side of the plate glass and thus overcome the reflection from the plate glass 5. 18 designates the rays of light that strike the bottom of the show window space 19, whereby the floor or bottom is fully illuminated.

The surface 14 may, if desired, be made curving instead of a flat surface, as shown.

The angle of inclination of the platform 3 serves to reflect the rays 13 substantially outward in a horizontal direction through the plate glass 5.

The ceiling 6 may, if desired, be omitted as it is not an essential part of my invention. The ceiling may be used for ornamental purposes, if desired.

It will be seen from this description that I have provided a simple and inexpensive means of illuminating articles of merchandise in the show window space and one that overcomes the objection of reflection from the outer surface of the plate glass of a show window.

What I claim is:

1. A show window construction for the purpose described comprising a transom member, or the like, for admitting rays of external light, a ceiling member spaced from the rear wall of the show case space, a reflector or other surface deflecting the rays of light from the transom member downward

through the said space onto an article of merchandise located within the show window space, whereby the light rays which fall onto the article of merchandise and are reflected outward through the plate glass or the main show window for the purpose of offsetting the outside rays which reflect objects on the outer side of the show window.

2. A store window construction which comprises an article display space, a main show window located at the forward edge of the display space, a transom or the like, arranged above the show window and separated by a ceiling partition which is spaced from the rearwall of the show window space, means for reflecting the light above the ceiling partition downward through said space onto an article located within the display space.
3. A store window construction comprising an article display space, a main show window located at the forward edge of the display space, a vertically arranged light admitting transom member arranged above the show window, means for reflecting the light admitted above the main show window onto an article located within the display space, and an auxiliary deflector means for deflecting rays of light upward toward the bottom or lower portion of an article of merchandise, whereby the entire article is lighted up.
4. In a show window construction, the combination with the main or front plate glass window, a transom or the like above the plate glass, a ceiling member arranged between the transom and the plate glass and terminating short of the rear wall of the show window construction to provide a space, means for deflecting the external rays of light which enter the transom through said space onto an article in the show window space, and an auxiliary reflector means for increasing the brilliancy of the article.

5. In a show window construction, in combination with a plate glass window, a transom, above the glass window in the same plane, means for reflecting an external source of light through the transom above the show window onto an article in the show window space at such an angle that the article is fully illuminated and the outside rays which would be reflected from the outer surface of plate glass obviated, as described.

CHARLES F. DINGMAN.
